CLAIM

The ornamental design for a baby crib, as shown and described.

DESCRIPTION

FIG. 1 is a front and top perspective view of a baby crib, showing my new design;

FIG. 2 is a rear and bottom perspective view thereof;

FIG. 3 is a front elevation view thereof;

FIG. 4 is a rear elevation view thereof;

FIG. 5 is a left side elevation view thereof;

FIG. 6 is a right side elevation view thereof;

FIG. 7 is a top plan view thereof;

FIG. 8 is a bottom plan view thereof;

FIG. 9 is another perspective view thereof, shown in an alternative position;

FIG. 10 is an enlarged perspective view of detail "10" identified in FIG. 1;

FIG. 11 is an enlarged perspective view of detail "11" identified in FIG. 1;

FIG. 12 is an enlarged perspective view of detail "12" identified in FIG. 2;

FIG. 13 is an enlarged perspective view of detail "13" identified in FIG. 2;

FIG. 14 is an enlarged perspective view of detail "14" identified in FIG. 2;

FIG. 15 is an enlarged perspective view of detail "15" identified in FIG. 5; and,

FIG. 16 is an enlarged perspective view of detail "16" identified in FIG. 8.

The dashed lines in the figures illustrate portions of the baby crib that form no part of the claimed design. The dash dot dash lines in FIGS. 1, 2, 5, 8, 10, 11, 12, 13, 14, 15 and 16 are for the purpose of depicting the boundary lines of the enlarged views and form no part of the claimed design.

1 Claim, 16 Drawing Sheets
